UNITED STATES PATENT OFFICE.

LORENZO MARTIN AVENSON, OF ST. PAUL, AND JOHN LEONARD HAGIE, OF MINNEAPOLIS, MINNESOTA.

LABEL FOR POISONOUS CONTAINERS.

Application filed October 3, 1921. Serial No. 504,909.

To all whom it may concern:

Be it known that we, LORENZO MARTIN AVENSON and JOHN LEONARD HAGIE, citizens of the United States, residing, respectively, at St. Paul, county of Ramsey, and Minneapolis, county of Hennepin, both in the State of Minnesota, have invented new and useful Improvements in Labels for Poisonous Containers, of which the following is a specification.

Our invention relates to improvements in labels for poisonous containers.

Its object is to provide, a simple and inexpensive article of this kind adapted to be conveniently attached to containers for poisons, whereby handlers thereof may be apprised, through the sense of touch, of the dangerous contents.

With the foregoing and other objects in view, which will appear in the following description, the invention resides in the novel combination and arrangement of parts and in the details of construction hereinafter described and claimed.

In the drawings, Fig. 1 is a perspective view of a label embodying our invention, the two members of the body being separated at one end to illustrate the method in which staples are applied thereto; Fig. 2 is an enlarged perspective view in detail illustrating one of the staples and Fig. 3 is an enlarged sectional view taken through the body of the article.

We have used the reference numerals 10 and 11, in the drawings, to indicate the front and back members, which comprise the body A of our improved label. These members are preferably pieces of paper. Staples B, having the heads 12 thereof bent at right angles to the prongs 13 (Fig. 2) are applied to the body member 10, by thrusting said prongs through said member and bringing the heads 12 against the back thereof (Fig. 1). The body member 11, having a coating of gum 14 or other adhesive material on the back thereof, is pasted

or otherwise bonded at its front side to the back of the body member 10. The heads 12 of the staples B, are held between said members 10 and 11, thus bracing the prongs 13 of the staples and securely anchoring the same in the body of the label. Lettering or other legible matter may be placed upon the face of the label, if desired, to serve the purpose of ordinary labels. Our label is proportioned in respect to the containers to which they are to be applied and so arranged thereon that the handler thereof will touch the label, the prongs 13 or pins projecting therefrom at once apprising him of the nature of the label. In employing our label for a poisonous container, one having access thereto is warned, through the sense of touch alone, of the dangerous contents and may, thereby, avoid unintentional use of the same.

It will be understood that changes in the specific form of our invention and in the materials and parts thereof, as herein disclosed, may be made within the scope of what is claimed without departing from the spirit of our invention.

Having described our invention, what we claim as new and desire to protect by Letters Patent is:

In a label, a body comprising two members, a plurality of pins reaching through one member and projecting from one side thereof, the heads of said pins bearing against the opposite side of said member to form bracing elements, the second member being applied to the first member to anchor the pins in the body and being gummed on its outer surface for applying the body to a container, said members being flexible and the pins arranged in rows to permit of close conformation of the gummed side of said body with a curved surface.

In testimony whereof, we have signed our names to this specification.

LORENZO MARTIN AVENSON.
JOHN LEONARD HAGIE.
